UNITED STATES PATENT OFFICE.

WILLIAM THOM, OF INDIANAPOLIS, INDIANA.

MACHINE FOR FLANGING SHEET-METAL CYLINDERS.

SPECIFICATION forming part of Letters Patent No. 398,673, dated February 26, 1889.

Application filed March 27, 1888. Serial No. 268,713. (No model.)

To all whom it may concern:

Be it known that I, WILLIAM THOM, of the city of Indianapolis, county of Marion, and State of Indiana, have invented certain new and useful Improvements in an Automatic Machine for Forming Flanges on the Edges of Sheet-Metal Cylinders, such as may be used in the manufacture of stove-pipe elbows, of which the following is a specification.

My said invention consists of an automatic machine whereby the operator, being relieved from all labor in the operation of the machine, (merely having to insert and remove the elbow-sections,) is thus enabled to handle the pieces with great rapidity and ease compared with such machines employing foot-power treadles. This machine may also be employed for forming a great variety of flanges on sheet-metal cylinders.

Referring to the accompanying drawings, which are made a part hereof, and on which similar letters of reference indicate similar parts, Figure 1 is a top plan view looking down from dotted line 1 1 in Fig. 2. Fig. 2 is a side elevation from the right in Fig. 3. Fig. 3 is a section on the dotted line 3 3 in Figs. 1 and 2. Fig. 4 is a section on the dotted line 4 4 in Fig. 3, looking to the right. Fig. 5 is a section of the lower part of the machine looking downward from the dotted line 5 5 in Figs. 2, 3, and 4. Fig. 6 is a section of the revolving head, showing its several working parts and relative position to the head-plate B through the dotted line 6 6 in Fig. 1. Fig. 7 is a plan of the revolving head looking down, the disk C⁴ removed. Fig. 8 is a cross-section of the revolving head H through the dotted line 8 8 in Fig. 7. Fig. 9 is a section on the dotted line 9 9 in Figs. 3 and 4. Fig. 10 is a section on the dotted line 10 10 in Fig. 1. Fig. 11 is a section on the dotted line 11 11 in Fig. 1. Fig. 12 is a section through the dotted line 12 12 in Fig. 1, the head H being omitted. Fig. 13 is a section through the dotted line 13 13 in Fig. 3. Fig. 14 is a detail elevation, partly in section, showing the collar, the standard, the sliding rods, and the manner of connecting the latter to the collar.

In said drawings, A A' A² represent the supporting-frame for the top plate, B, and other mechanism, the top of said frame being

secured to plate B, and the bottom to bridge-tree A⁵. The driving-shaft E has its bearings in the lug A⁶, which is secured to the frame A². On the outer end of said driving-shaft E are mounted the pulley or pulleys E' E², and toward the inner end of said shaft is the pinion I, which drives the spur-wheel J on the counter-shaft K, (on which are also mounted the cams M', M², and N,) which has its bearings in boxes A³. The bevel-gear F, rigidly secured on the inner end of shaft E, drives the bevel-gear G, which is rigid on the hub of the head H, which carries the slides and central mechanism, which is more particularly described hereinafter.

The central stationary standard, C, rests in the box A⁷, which in turn rests in the bridge-tree A⁵, and is horizontally adjustable therein by means of the lugs A⁸ and set-screws A⁹, and has a vertical adjustment by means of the set-screw A¹¹ and the lock-nut A¹². The set-screw A¹³, Fig. 2, holds the standard C rigidly and prevents its turning in the box A⁷. Said stationary standard C has four grooves, C², extending along its sides nearly its entire length, to receive the rods C', which are connected at the bottom to the collar T by means of the pins or studs a, which are held therein by their squared shoulders in key-rings b, which are screwed on said collar T. The upper ends of rods C² are secured by means of shoulders, as best shown in Fig. 6, to the cone C³, which expands or throws out the friction-rollers f, mounted in the inner ends of sliding forming-wheel carriers e³.

The supporting-bracket or bridge-tree D is secured to the top plate or frame, B, and supports the central standard, C, and the head H, which has its bearing in the collar G'. The collar G' and standard C are adjusted or centered by means of the set-screws G³. The gear-wheel G is adjustable on the head of the hub H by means of the set-screw G².

The head H consists, essentially, of a cast-iron head having grooves H² planed in its upper surface, forming ways to receive the sliding carriers e³, which are mounted in the slots e⁵ on the studs e⁴, which are adjustable with a nut, e⁷, in said slots e⁶ and serve as journals for the forming-rollers e⁵. In the outer ends of the carriers e³ is a small orifice, e, to receive the spiral spring e², which, be-

ing compressed therein between the outside plate, e' , (which is screwed to H .) and the inner end of the orifice e , keeps the carriers e^3 pushed inward except when forced outward 5 by the downward movement of the cone C^3 . The inner ends of the carriers e^3 are provided with friction-rollers f , which have their axes on the studs g , as best shown in Fig. 6. The head H runs upon and around the central standard, C , and has its bearings on the collars $H' H^3$, which are rigid with the standard C . The lower end of the hub H is partly supported by the collar U , with the set-screw U' on the shaft C . On the top of the standard C (which is reduced in size) is the guiding-disk C^4 , which is capable of adjustment thereon by means of the set-screw C^6 .

C^5 represents metal which has been poured in molten condition on the top or upper surface of said disk or guide C^4 (while an elbow-section is inserted thereon) to form an even bearing or support all around the inside of the elbow-section while the same is being operated upon in said machine.

25 The lever P is fastened to the lower frame, A , by the bolt P^0 , on which it swings, and is provided with a friction-roller, P' , as a bearing for the cam M' , and is connected with the upright rod P^3 at P^2 . The top arm or lever, P^6 , has its fulcrum on the pivot P^5 in the lug B' , and is connected at its upper end by the screw P^7 to the hood Q . The screw P^7 works loosely in the end of the lever P^6 , and when properly adjusted the limit of movement is 35 regulated by the nuts P^{10} . The spring P^{11} acts as a cushion for the stroke of the hood Q and compensates for the variation in the size of the elbow-sections, giving the stroke an elastic movement. The lower end of screw P^7 is provided with a ball-joint, which has its bearing in the hood Q and the plate P^9 , which is secured by bolts P^8 to the hood Q .

The lever O , as best shown in Fig. 2, is pivoted to the frame A at O^0 , and is held against the cam N by the spring V , and has a friction-roller, O^5 , in its curved end, which the cam N turns upon. The rod O' connects the cam-rod O^2 and the lever O at O^3 and O^6 . The cam-rod O^2 has its bearing in the lug O^7 and 45 the top frame, B , its cam-face bearing and working upon the friction-roller B^4 , which revolves in a bearing, B^8 , pivoted by B^6 to the ring B^2 , thus admitting of a swivel movement to accommodate the vibrations of the ring B^2 55 in its oscillations by the action of the cam O^2 when pulled down and when returned by the spring g . The lug D' , which is bolted to the bracket D , acts as a support for the fork-lever R , which is pivoted thereto by 60 the stud D^3 . One end of said lever R partly surrounds and is connected to the collar T by the studs c , and the curved end is provided with a friction-roller, R^2 , as a bearing for the cam M^2 . The ends of the spring S are secured at R^3 and S' . Said spring serves to return the levers P and R when released by the cams M' and M^2 . The top plate, B ,

has a groove or recess turned out on its upper surface to receive the ring B^2 , which is connected to the lower slides, k , which move between the ways B^5 by the links j and the studs $j' j^2$. The cast-iron jaw-plates h are secured to the slides k by means of the bolts h' and are capable of slight adjustment longitudinally through the slots in their outer ends 75 and the set-screws i in the projections k' . The steel dies n are secured to the jaws h by means of the screws l , and are raised and lowered by means of the set-screws m . The jaws k are slid toward and from a common center in the ways B^5 by the action of the ring B^2 . The gage-plate p (on which the elbow-section rests while being operated upon) is fitted into a recess, p^3 , in the top plate, B , (best shown in Figs. 6 and 12,) and has a vertical adjustment 80 by means of the set-screws p' .

The operation of my machine may be briefly recapitulated as follows: As before stated, the machine is automatic and continuous in its operations whenever the power is applied 90 to it, as will be better understood from the following description. In Fig. 2 the elbow-section W has been inserted while the hood Q is at rest; but when the friction-roller P' has traveled from M^3 to M^4 on the idle periphery of 95 the cam M' and passes the point M^4 said cam suddenly forces down the lever P , and, through the connecting-rod P^3 and the arm P^6 , the hood Q is brought down, bearing evenly on the elbow-section W , thus holding it in proper 100 position to be grasped and securely held by the steel dies n , which are simultaneously thrown in by the action of the cam N , depressing the lever O' . The cam-rod O^2 is pulled down by said lever O and connecting-rod O' , and the face of the cam O^2 , coming in 105 contact with the friction-roller B^4 , causes the ring B^2 to oscillate, and thus, through the links j and studs $j' j^2$, the jaws k and the steel dies n are put into position, as best shown in 110 Figs. 3 and 4. While the two cams M' and N have put the hood Q and the steel dies n into the proper position, as above described, the forming-rollers are next thrown out and put into operation on the metal cylinder W by the 115 cam M^2 engaging the friction-roller R^2 , forcing down the inner end of the fork-lever R' , with the collar T , and, through said collar and studs a , the inlaid rods C' are drawn down, and with them the cone-collar C^3 , which, 120 bearing on the cone-rollers f , expands the sliding carriers e^3 , on which are mounted the forming-wheels e^5 , thus engaging them with the raw edge of the sheet-metal cylinder against the steel dies n , thus completing the 125 operation. On further movement of the driving mechanism the cam M relieves the lever P . Then the cam M^2 relieves the lever R , and, lastly, the cam N relieves the lever O , when the springs S , V , and e^2 return the hood Q , 130 the cone C^3 , the sliding carriers e^3 , and the cam O^2 to the former positions, respectively, for successive operations.

Having thus fully described my said inven-

tion, what I claim as new, and desire to secure by Letters Patent, is as follows:

1. In an automatic machine for forming flanges on sheet-metal cylinders, the combination, with a rotating head carrying radially-sliding carriers in which are journaled the flanging-rollers, of a support for the sheet-metal section, an arm, P⁶, carrying a hood, Q, a lever, P, connected to said arm, the rods C', carrying the cone-collar C³ and collar T, a lever, R, connected to the collar T, and a shaft having cams actuating the levers P and R, substantially as described.

2. The combination, with a rotating head carrying radially-sliding carriers in which are journaled the flanging-rollers e⁵, of a support for the pipe-section, a series of slides moving in ways toward and from said support, said slides having jaw-plates h, a ring, B², to which the slides are linked, a cam-slide, O², working in a slot in said ring, a lever, O, connected to said slide, a cam, N, on counter-shaft K, rods C', carrying the cone-collar C³ and collar T, a lever connected to the latter collar, and a shaft having a cam, M², substantially as described.

3. The combination, with the revolving head H, carrying the sliding carriers e³, having forming or flanging rolls e⁵ and retracting-springs e², of the standard C, the rods C', moving in channels in said standard and carrying the cone-collar C³, a lever, R, fulcrumed on a bracket, D', and connected to a collar, T, on the rods C', a cam, M², on a counter-shaft, a support, C⁵, for the pipe-section, slides having clamping-jaws h, surrounding said support, and means for moving said slides toward and from the latter, substantially as described.

4. The combination, with the revolving head H, having grooves H², of the carriers e³, the studs e⁴, adjustable thereon, the flanging-rolls e⁵, mounted on said studs, the rods C', carrying the cone-collar C³ and having the collar T, the lever R, cam M² on counter-shaft K, a support for the pipe-section, and movable jaws for clamping the latter, substantially as described.

5. The combination, with the rotating head H, having grooves, of the carriers e³, the adjustable flanging-rolls e⁵, the rods C', arranged in channels in the standard C and carrying the cone-collar C³ acting upon friction-rolls f on the carriers, the slides k, linked to the ring B² and having clamping-jaws h, said slides moving between ways B⁵, a support, C⁵, for the pipe, a lever, P⁶, carrying a hood, Q, a lever, P, connected to said lever, a lever, R, connected to a collar, T, pinned to the rods C', a cam-slide, O², bearing on a friction-roll, B⁴, on the ring B², a lever, O, connected to the cam-slide, and cams M', M², and N on the counter-shaft K, substantially as described.

6. The combination, with the revolving head H, having ways H², of the carriers e³, having the adjustable rolls e⁵ and friction-rolls f, and provided with openings e to receive springs e², of the rods C', moving in channels in the standard C and carrying the cone-collar C³, said rods provided with the collar T, the lever R, connected to said collar, the counter-shaft K, having a cam, M², a support for the pipe-section, and means for clamping the latter upon said support, substantially as described.

7. The combination, with the revolving head H, having grooves, of carriers e³, having grooves e⁶, the flanging-rolls e⁵, mounted on studs e⁴, adjustable in said grooves, the support B, having ways B⁵, the slides k, moving therein and having steel jaws n mounted on the clamping-jaws h, the rods C', carrying the cone-collar C³ and connected to the collar T, a support, C⁵, for the pipe, a lever, R, connected to the collar T, a cam, M², on counter-shaft K, a ring, B², moving on the support B and connected to the slides k by links j, the cam-slide O², the lever O, connected thereto, the cam N on shaft K, and the head-spring q, connected to support B and ring B², respectively, substantially as described.

8. In an automatic machine for forming flanges on sheet-metal cylinders, the supports e⁵ for the cylinder or pipe, the hood Q, the connected levers P and P⁶, the latter having an eye which receives the rod P⁷ on the hood and provided with a cushion-spring, P¹¹, and the cam M' on the counter-shaft K, substantially as described.

9. The combination, with the lever P, arm P⁸, and lever P⁶, having an eye receiving the threaded rod P⁷ on the hood Q, the latter having a socket receiving a ball on said rod, of the cushion-spring P¹¹, the nut P¹⁰, turning on the threaded rod P⁷, and the cam M' on the counter-shaft K, substantially as described.

10. The combination, with the top plate, B, having an orifice, of the gage-plate p, the set-screws p', the carriers e³, having adjustable flanging-rolls e⁵ and moving in ways in the revolving head H, the rods C', carrying the cone-collar C³, bearing upon friction-rolls f, a support for the pipe, movable clamping-jaws, a lever, R, connected to a collar on the rods C', a cam, M², on a counter-shaft, K, and means, substantially as described, for operating the clamping-jaws, substantially as described.

In witness whereof I have hereunto set my hand, at Indianapolis, Indiana, this 3d day of March, A. D. 1888.

WILLIAM THOM.

In presence of—
AQUILLA Q. JONES,
J. W. JONES.
